UNITED STATES PATENT OFFICE

WILHELM HEISINGER, OF BERLIN-ZEHLENDORF, GERMANY, ASSIGNOR TO REMINGTON RAND INC., OF BUFFALO, NEW YORK

SHEET-HOLDING ATTACHMENT FOR CARD-INDEX TRAYS

Application filed October 13, 1930, Serial No. 483,491, and in Germany May 25, 1929.

This invention relates to a sheet holding attachment for card index trays, and particularly trays constructed and equipped with overlapping offset card holders having visible indexes in which the card holders are hinged so that any overlapping card holder may be moved on its hinge to expose the record on the card holders thereunder.

The sheet holding attachment is particularly adapted for use in connection with the visible index equipment disclosed in copending application, Serial No. 871,153, filed June 15, 1929.

The invention comprehends the provision of a plate member provided with suitable means for holding and guiding a sheet so that the sheet may be slidably moved over the plate member to a desired extent, in which the plate member is adapted for slidable attachment to the side edge of a card index tray equipped with card holders having folded sheets so that one flap portion of the folded sheet may be swung upwardly to permit the insertion of the plate member and sheet carried thereby under the upwardly extended flap portion, which may subsequently be placed over the top of the plate member and record sheet thereon, so that a record may be simultaneously entered on the flap portion of the folded sheet overlying the plate member and the record sheet on the plate member by means of transfer paper when the two sheets are brought into proper registry with one another.

The invention further comprehends the provision of means on the plate member for readily and detachably connecting the plate member to one side of the tray, so that it is slidably supported and guided thereon, together with means which will hold hinged pocket members which have been laid back by hinged movement from their normal visible index position so as to expose the record on one card holder in this laid back position, while an entry is being made on the record sheet carried by the plate member of the holding attachment.

This invention further provides for the rapid manipulation of visible card holders for the entry of records thereon and for the

making of duplicate records on a sheet or sheets carried by the holding attachment in which these sheets can be placed in proper position for the entry of the record in a convenient manner, and at the same time provides a writing surface for supporting the portions of the sheet on which records are being made. Provision is further made by the slidable mounting of the record sheet on the plate member of this holding attachment, to permit the adjustment of the sheet relative to the plate member so that it may be properly aligned with a portion of a folded record sheet carried by a card holder mounted in the tray.

The invention comprehends numerous other features residing in the details of construction of the holding attachment and the manner of mounting the same on a card index tray, together with the combined features of the holding attachment with the record sheet thereon and the records on the card index tray, all of which are more particularly pointed out in detail in the following description, and set forth in the claims.

In the drawings forming part of this application:

Fig. 1 is a plan view of a card index tray equipped with a series of overlapping offset card holders having detachable folded sheets and the sheet holding attachment applied to the tray in an operative position with a record sheet thereon illustrating the manner in which the invention is used.

Fig. 2 is a side elevation of a tray and holder as shown in Fig. 1.

Fig. 3 is a longitudinal sectional view taken on line 3—3 of Fig. 1.

Fig. 4 is a transverse sectional view taken on line 4—4 of Fig. 2.

Fig. 5 is a bottom perspective of the holder detached from the tray.

The sheet metal tray 1 is a conventional type of construction used in conventional visible index equipment and the tray illustrated is formed of a single sheet of metal having a bottom 2, side flanges 3 extending upwardly from the side edges of said bottom and turned inwardly and downwardly as indicated at 4 to provide guide channels at the

opposite sides of the tray to receive the ends of lugs or holder members 5 to each of which is hingedly connected a card holder 6. The holder members 5 have their usual function 5 of spacing the overlapping card holders in offset relation so that the free margin of each card holder is visible for visible indexing purposes. Folded record sheets 7 are detachably connected to the card holder in any de- 10 sired manner such as illustrated in the afore- mentioned application, and have a bottom flap portion 8 provided with portions connected to the card holder 6, while the upper flap portion 9 is free for hinging movement 15 at the fold portion relative to the bottom portion 8. All of the fold portions of these sheets 7 are arranged in substantial alignment and at one side of each of the card holders so as to lie adjacent to one side of the 20 tray so that the flap portions 9 of these sheets will hinge in a plane substantially at right angles to the hinging or swinging movement of the card holders 6. However, this relation of the folded sheet to the card holder is only 25 for the purpose of illustration and other ways of securing the similar results are comprehended by the invention.

The sheet holding attachment of this invention comprises a plate member 10 formed 30 of sheet metal and provided with upwardly and inwardly directed flanges 11 at the side edges to provide guide channels for slidably receiving and retaining a record sheet 12 on the upper face of the plate member 10. One 35 end of the plate member, that end which is normally directed toward the rear end of the tray, is formed with an upwardly curved portion 13 which is adapted to overlie the card holders above the one on which a record 40 is being made in a laid-back position on their hinged connections with the lugs 5 in the manner illustrated in Fig. 3. The opposite end of the plate member 10 is formed with a downwardly curved extension 14 which is 45 normally directed toward the front end of the tray so that the sheet will not be creased along the edge of the plate 10 in the use of the attachment by the person operating the attachment resting his hand on the forward 50 edge of the holder, or that portion directed toward the front of the tray. This extension 14 also serves as a hand rest so that a person using the attachment can conveniently write on the record overlying the plate member 10.

55 A special bracket member 15 is applied to the bottom face of the plate member 10 in the manner illustrated, and is formed of a strip of sheet metal having one end secured to the plate member as indicated at 56 by 60 spot welding or the like, adjacent to which is a curved section 17 curving outwardly and downwardly toward the adjacent side edge of the plate member, this curved portion 17 being inclined relative to the plane of the 65 plate member 10 so that the plate member

may assume the inclined relation to the tray shown in the drawings in Figs. 2 and 3. A section 18 extends from the edge of the section 17 and extends substantially at right angles to the plate member 10 as illustrated 70 in Fig. 4, and toward the plate member 10, where it is connected to the section 19 suitably secured to the plate member. A section 20 of the bracket 15 extends laterally from the section 19 away from the plate member 10 and terminates in a lateral projection 21 at the opposite end of the strip forming this bracket. The section 20 is parallel to the section 18 and with the section 19, provides a channel shaped member of a size to receive the flange portions 3 and 4 at one side of the tray, as illustrated in Fig. 4, so that the holder member may be slidably positioned on the side edge of the tray, while the lateral extension 21 forms a lip to extend 80 under the bottom of the tray in the manner illustrated, to permit the slideable movement of the holder on the tray but prevent accidental detachment thereof from the tray. The section 20 is sufficiently resilient so that the bracket member may be positioned over the upper edge of the flange portion of the tray, and when the channel shaped portion of the bracket is engaged over the flanges in the proper manner, the lip 21 will snap into 90 position under the bottom of the tray. 95

It will be noted that the bracket member 15 is applied to one side of the plate member 10 and that all portions of this bracket member as above described, are inclined longitudinally relative to the plate member 10. This is to permit the support of the plate member 10 in the inclined position illustrated in the drawings when it is applied to the tray. This inclined position is such that the plate member 10 will lie substantially flat on the overlapping offset card holders in the tray which are themselves inclined in the manner shown in Fig. 3, and also overlie one side of the tray. 105 110

With a record sheet 12 applied in the holder in the manner illustrated, for the purpose of making records thereon, in the operation of and use of this invention, the holder is applied to the tray in the manner shown and 115 above described, the card holder on which a record is to be made being previously selected, and those overlapping card holders lying on the selected card holder being moved upwardly about their hinges so as to lay back 120 against the upper or inner end of the tray, in the manner shown in Fig. 3. The holder is then applied and moved into position so that the upwardly curved portion 13 will overlie the portion of the card holders laid back upon their hinges adjacent to their hinge connections so that they will be retained in the laid back position while the plate member 10 overlies the card holder on which the record is to be made. Previous to 125 130

the application of the holder to the tray, the upper flap portion 9 of the record sheet on the selected card holder is hinged outwardly about its fold portion and after the holder is applied, this flap portion 9 is then moved so as to overlie the plate member 10 and the record sheet 12 thereon in the manner shown in Fig. 1.

It will be noted, as illustrated in Fig. 1, that the edge of the holder opposite to the portion secured to the edge of the tray terminates inwardly of the opposite edge of the tray and also the line of the folds of folded sheets 7 so that the edge of the holder will lie within the folds of these folded sheets in the manner illustrated in Fig. 4. With a piece of carbon paper applied over the sheet 12 and under the flap portion 9, and the sheet 12 moved on the holder so as to align the proper portions of this sheet with the corresponding portions of the flap portion 9, the record entry can then be made and a copy will be made on the sheet 12 as it is entered on the flap portion 9.

This facilitates the making of records so that in addition to the original entry made in the visible index, a current entry can be made on the sheet 12 which may be used for accounting or other purposes in connection with the keeping of accounts or stock records or any other type of record where more than one entry is desired in making the records.

The plate member 10 of the holder provides a convenient writing surface as well as a convenient support for the hand of the operator or person making the record and operating the index and permits the progressive sliding of the sheet 12 in the holder so that successive entries on different folded record sheets in the index can be entered one below the other on the record sheet 12.

The invention comprehends the provision of this novel holder structure, in addition to the combination between the holder and the tray with its associated hinged card holders or record cards as the case may be, and the associated folded record sheets or cards, and it is to be understood that any combination of these elements for accomplishing this plural entry of records with the use of a holder device of the character disclosed is included within the scope of this invention.

What is claimed is:

1. A sheet holding attachment for card index trays comprising a plate member forming a writing support for sheets and having guide means at the side edges for slidably and detachably retaining a sheet thereon, and a bracket on said plate member formed for slidable and detachable engagement with a side of a card index tray for slidably supporting said plate member thereon.

2. A sheet holding attachment for card index trays, wherein each tray is provided with channels at the side edges and a plurality of

card holders arranged in offset overlapping relation are hingedly connected to supporting means detachably engaged in said channels, a folded record sheet having one flap portion detachably secured to each card holder, the fold portions of all of said sheets being arranged adjacent to one side of the tray, and the other flap portion of said folded sheets being free; comprising a plate member, means for detachably retaining a record sheet thereon, and means for slidably and detachably connecting said plate member to the side of said tray opposite the fold portions of said folded record sheets, said plate member being arranged to have an edge parallel to said fold portions engage between the flap portions of said folded sheets with the free flap portion overlying the plate member for the entry of record data thereon and on the record sheet on said plate member.

3. A sheet holding attachment for card index trays, comprising a plate member, guide flanges on the side edges of said plate member, an upwardly curved extension at one end of said plate member, a downwardly curved extension at the opposite end of said plate member, and a bracket member for detachably and slidably supporting said plate member on a card index tray.

4. A sheet holding attachment for card index trays, comprising a plate member, guide flanges on the side edges of said plate member, an upwardly curved extension at one end of said plate member, a downwardly curved extension at the opposite end of said plate member, and a bracket formed to embrace one side of a card index tray for slidably and detachably supporting said plate member thereon.

In testimony whereof I have hereunto set my hand.

WILHELM HEISINGER.
